UNITED STATES PATENT OFFICE

GEORGE L. DENNIS, OF WASHINGTON, DISTRICT OF COLUMBIA

TABLE

Application filed April 1, 1930. Serial No. 440,663.

My present invention relates to improvements in tables of the type which includes foldable legs and foldable leaves, and which are adapted to be knocked down and compactly arranged for storage, when not in use. While the table of my invention is well adapted for many domestic uses, it is especially designed for use in dining rooms, restaurants, banquet halls, and other public eating places 10 where it is frequently necessary to remove tables from the dining room and store them in a store room.

In carrying out my invention, I provide the tables with means whereby they may quickly 15 be knocked down or folded into compact form and securely fastened so that the tables may be stacked in convenient piles in the store room, and thus arranged to occupy only a minimum storage space. Means are also provided whereby the tables may quickly and 20 with facility be set up and locked in set position for use, either singly to accommodate a small dinner party, or in coupled rows to form a long sectional table for a large dinner 25 party, as well as for banquets.

The parts of my improved table are so combined and arranged that when the table is set up a maximum space is provided for the feet and legs of the diners, and unnecessary 30 obstructions are removed from under the table. When set up singly, the table is securely braced to insure stability, and when the 35 tables are set up and coupled to form a long sectional table, as for a banquet, the sections are rigidly coupled together and the several 40 tables form a stable, long table.

When the tables are knocked down and 45 their parts secured together, they are retained in a comparatively small compass in order that the packed tables may be handled with facility.

By utilizing the devices of my invention in 50 the table construction, I am enabled to employ a minimum number of waiters for carrying the tables to and from the storage room and the dining room, thus attaining a saving in time and labor employed, and confusion is avoided permitting the transportation of the tables to be accomplished in an orderly manner.

While I have referred to the use of my portable, knock-down table, in a dining room or other public eating place, it will be understood that the table may be used for household purposes and in various other ways. 55

The invention consists in certain novel combinations and arrangements of parts that enable me to attain the above indicated results, and as hereinafter set forth and claimed.

In the accompanying drawings, I have illustrated one complete example of the physical embodiment of my invention wherein the parts are combined and arranged according to the best mode I have thus far devised for the practical application of the principles of 60 my invention.

Figure 1 is a vertical section view of the table set up.

Figure 2 is a sectional view at right angles to Figure 1, with one of the leaves turned 70 down.

Figure 3 is a plan view of the table folded and packed, ready for storing.

Figure 4 is an end view of a packed table, showing by dotted lines how the packed 75 tables are stored or stacked.

Figure 5 is an enlarged detail view at one end of the removable and interchangeable brace bar, and

Figure 6 is a plan view of co-acting fastening devices on adjoining tables for coupling 80 them together.

In carrying out my invention, the portable, knockdown or collapsible table is fashioned with a top 1 to which are hinged two folding leaves 2 and 3, the hinges being indicated at 4. While the top may be fashioned in any selected and suitable shape, I prefer to employ a square table having an area of about a square yard, and the free edges of the square 90 table top fit neatly against those of an adjoining table to insure a smooth surface when a plurality of tables are coupled together to form a sectional table.

The leaves, as indicated, are designed to 95 fold to position at right angles to the main table top, and under some conditions they may assume this position when table is set up. When the table is knocked down, the leaves are turned at right angles to the top 100

and rigidly secured in that position in order that the compacted table may be stacked as indicated in Figure 4. When the compacted tables are stacked, the lower edges of the folded leaves of an upper table rest in the lateral grooves formed along the hinge joints of the table beneath, and in this manner the stack or pile of compacted tables is held or retained against displacement of the tables in the stack or pile.

The table is provided with a pair of spaced legs 5 and 6, each of which is fashioned with a transversely arranged foot bar 7 at the ends of which are provided swiveled casters 8. The legs are fashioned with top hinge bars 9 which also extend transversely of the table and parallel with the foot bars, and at 10 the hinge bars are hinged to hinge-blocks 11 and 12 that are securely fastened to the underside of the table top.

It will be noted that one of the legs is longer than the other and, consequently, one of the hinges is spaced below the table top a greater distance than the other hinge joint, in order that the legs may be folded flat against the underside of the top for packing.

The hinged leaves 2 and 3 may be turned down to vertical position, as indicated by dotted lines in Figure 1, while the table is in position for use, and the leaves are also turned to this position, as seen in Figures 3 and 4, when the table has been knocked down and secured for storing.

The legs are thus hinged on joints disposed at right angles to the hinge joints of the leaves, and because of the difference in the width of the hinge blocks 11 and 12, the legs are permitted to fold, one over the other, parallel with the underside of the top. The leaves, when folded to right angle positions relative to the top, form the sides of an enclosure for the folded legs, and it will be apparent that the lower edges of the leaves of an upper knocked-down table will fit into the lateral grooves of the table beneath, thus permitting the tables to be stacked as in Figure 4.

When the table is set up for use, the two leaves are supported flush with the top by means of four wood bars 13, each provided with a knob 14 and pivoted at 15 on the underside of the table top. The pivot 15 may be a stud bolt secured in the top and provided with a butterfly nut 16 which is secured against turning by means of a staple 17 driven into the underside of the top and over one of the wings of the nut, but any suitable means may be employed for preventing dislocation of the parts. The pivoted wood bars are of sufficient length to project beneath the leaves and support them, when the bars are turned to extended position as shown in Figure 1, and they provide the necessary rigidity and stability for the table leaves.

When the table is to be set up, the legs are

swung to position perpendicular to the top, and then they are braced apart by the use of a removable and interchangeable brace bar 18 that is fashioned with two end heads 19. These heads have squared edges to fit against the faces of the legs and also against the under faces of the hinged leaves, and their ends are recessed or cut away, each to receive a flanged plate 20 that is secured as by a screw 21 in the recessed edge of the head.

Each plate 20 is fashioned with a pair of hooks 22 located within the recess of the head, and these hooks are designed to engage, alternately, complementary eyes 23 on the legs and eyes 24 on the leaves. The eyes 23 and 24 are integral with plates 25 that are mortised in the surfaces of the legs and of the leaves and secured by screws.

Each head of the brace bar is provided with a slide bolt 26 adapted to engage in a socket 27 in an adjoining leg and also in an adjoining leaf of the table, and the bolt is supported in a face plate 28 secured to the head end slotted at 29 to accommodate the push pin 30 of the bolt. The bolt may reciprocate longitudinally in the bore 31 of the head, guided by the flange 32 of the face plate, which is perforated for the purpose.

After the hooks on the brace bar have been engaged in the eyes of the table-legs or of the table-leaves, the bolts are slid to extended position, and the brace bar is thus fastened against longitudinal movement as well as against edgewise movement and the bar and leaves, or the bar and legs, are rigidly joined together to provide a stable formation of the parts.

As thus described, it will be apparent that the table may be set up to form a rigid and stable structure sufficient to resist displacement when bumped by the knees or by the feet, and the arrangement of the legs at the center of the table with the foot bars of the legs close to the floor, provides ample room beneath the table for the feet and legs of the diner.

In preparing for a large party of diners, as for a banquet, the tables are joined together by couplings at their adjoining ends, and as these ends are squared, the plurality of tables may rigidly be joined together to form a long, sectional table that is rigid and stable.

At the opposite ends of the table top, and to its underside are secured or mounted the complementary coupling members in order that a latch on one top may be secured to the keeper on the top of the adjoining table. Thus each table has at one end a latch 33, with a handle 34, and pivoted at 35 in the ear 36 of a latch plate 37, that is secured at the underside of the table top. The latch has a lug 38 thereon for frictional engagement with a detent 39, secured on the top, and used

with the latch to hold it retracted when the latch is not to be used.

At the opposite end of each table is mounted a keeper 40 struck up from its plate 41, which plate is secured to the top, and the latch is designed to swing into frictional contact with the keeper and plate and under the keeper. A locking lever 42 is pivoted at 43 adjacent the keeper, and this lever has a friction lug 44 bent up at its free end, to engage the latch and hold it from displacement. Thus each table is equipped at its ends with complementary coupling members designed to co-act similar members on the two adjacent joining tables.

Having thus fully described my invention, what I claim as new and desire to secure by Letters Patent is:

1. The combination in a portable, knock-down table having a pair of hinged leaves, of a pair of hinged legs, a removable and interchangeable brace bar, fastening means on the leaves and legs, and complementary fastening means on the brace bar for alternate use with the fastening means on the leaves and legs.

2. The combination in a portable, knock-down table having a pair of leaves and fastening eyes on the leaves, of a pair of hinged legs and fastening eyes on the legs, a removable and interchangeable brace bar, and fastening hooks on the brace bar for alternate use with the eyes on the leaves and legs.

3. The combination with a table having a pair of spaced hinged legs and eyes on the adjoining sides of said legs, of a removable brace bar having complementary hooks to fit said eyes, and fastening bolts in the bar adapted to engage sockets in the legs to prevent edge-wise movement of the bar.

4. A table comprising a top and pair of hinged leaves, movable supports on the top for holding the leaves extended, a pair of hinged legs for the table, a brace bar adapted to confine the folded legs against the underside of the table when the leaves are turned at right angles to the top, fastening means on the leaves, and co-acting fastening means at the opposite ends of the brace bar.

5. A table comprising a top having a pair of leaves hinged to its edges and fastening devices on the leaves, a pair of spaced legs hinged to the top at right angles to the leaves and between the leaves and adapted to fold against the top, a removable brace bar adapted to confine the legs in folded position, and fastening devices on the ends of the brace bar for engaging the devices on the leaves when the latter are turned at right angles to the top.

6. A table top having a pair of hinged leaves and a pair of eyes on the underside of each leaf, a pair of legs hinged to the top at right angles to the hinges of the leaves and adapted to fold on the top, a pair of eyes mounted on each leg, an interchangeable

brace bar having a pair of hooks at each end, and movable supports mounted on the table top for holding the leaves flush with the top, the hooks on the brace bar being adapted for engagement with the eyes of the legs, and alternately for use with the eyes of the leaves when they are turned at right angles to the top thereby holding the legs in folded position against the top.

In testimony whereof I have affixed my signature.

GEORGE L. DENNIS.
